UNITED STATES PATENT OFFICE.

CHARLES C. HANSEN, OF FOREST PARK, ILLINOIS, ASSIGNOR TO REFRIGERATING SPECIALTIES COMPANY, OF CHICAGO, ILLINOIS, A CORPORATION OF ILLINOIS.

REFRIGERATING APPARATUS.

1,402,418.

Specification of Letters Patent. Patented Jan. 3, 1922.

Application filed February 23, 1916. Serial No. 79,813.

To all whom it may concern:

Be it known that I, CHARLES C. HANSEN, a citizen of the United States, and a resident of Forest Park, in the county of Cook and State of Illinois, have invented certain new and useful Improvements in Refrigerating Apparatus, of which the following is a full, clear, and exact description.

The invention relates to refrigerating apparatus and more particularly to mechanism for automatically controlling it responsively to variations in the temperature in the room or apartment to be refrigerated.

In automatic refrigerating systems, in which a cooling liquid for the refrigerant-condenser is used, it has been found necessary to avoid operation of the refrigerant pump or compressor, if for any reason the supply of the cooling liquid is insufficient or should fail. One object of the present invention is to provide improved controlling mechanism which will keep the compressor idle despite temperature changes in the room or space being cooled, if the supply of cooling liquid, usually water, should fail or its pressure should fall below the maximum desired for proper degree of condensation or cooling of the refrigerant.

A further object of the invention is to provide improved thermostatic controlling mechanism for the motor for driving the compressor, in which provision is made for snapping a lever-switch into and out of closed position to prevent sparking at the switch-contacts.

A further object of the invention is to provide improved controlling mechanism for automatic refrigerating systems.

The invention consists in the several novel features hereinafter set forth and more particularly defined by claims at the conclusion hereof.

In the drawings: Fig. 1 is a vertical section of the improved controlling mechanism, parts being shown in elevation. Figs. 2 and 3 are end elevations viewed from opposite sides respectively, the case for enclosing the starting mechanism being shown in section. Fig. 4 is an elevation of the switch for controlling the motor for driving the compressor, the cover of the case being removed. Fig. 5 is a section taken on line 5—5 of Fig.

1. Fig. 6 is a diagram of the electrical connections and the refrigerating system.

Referring to the diagram (Fig. 6), 10 denotes a pump or compressor for the refrigerant; 11 a refrigerant line suitably connected to the pump; 12 a condenser coil in a suitable tank 14 and connected to receive the refrigerant from the compressor; 15, a receiver for the refrigerant; 17 a motor for driving the compressor, and 18 a pipe which supplies cooling water to the refrigerating system for condensing the refrigerant in coil 12.

Motor 17 is connected to be supplied with current from a pair of line-conductors 18 and 19, a switch comprising contacts 20 and 21 and a lever 22 being included in one of the line-connections to control the operation of said motor.

A starting motor 23 is employed to furnish the power for operating the switch-lever 22. A thermostat 24 of suitable construction and disposed in the refrigerating room or space, which is conventionally indicated at *a* and is connected to control the electrical connections for starting the motor 23. The connections for this purpose comprise a conductor 25 between the line-conductor 19 and one of the brushes on the motor 23; a conductor 26 connecting the other brush of said motor and a thermostat-contact 27; a conductor 28 connecting the line-conductor 18 and another thermostat-contact 29; a rotating notched disk or member 30 driven by suitable gears operated by motor 23; a brush-contact 31 connected to conductor 26; a brush-contact 32 connected to thermostat 24 and a brush-contact 33 electrically connected to the conductor 28.

Motor 23 is mounted upon a bracket 34 which is adapted to be secured to some suitable convenient support. A hood 35 on top of bracket 34 encloses said motor and its associated parts. The gearing between the motor 23 and the controller-member 30 comprises, a worm 36 fixed to the shaft of the motor; a gear 37 meshing with said worm and fixed to a vertical shaft 38; a worm 39 on said shaft 38 meshing with a suitable gear 40, and a shaft 41 on which a controlling member 30 is mounted. The motor-casing is supported on posts 42. Upright

shaft 38 is suitably mounted in bearings 43 and 44. Shaft 41 is mounted in bearings 45, 46. Contacts 31, 32, and 33 are secured to studs 47, respectively, and all of these studs 5 are mounted in and insulated from a bracket 48 secured to supporting bracket 34.

A supply pipe 50 for cooling water is connected to a valve-casing 51. Pipe 16 for conducting water to the condenser is also connected to an outlet in this casing. At the inlet-side of the casing, a valve 52, normally closed by a spring 53, controls the flow of the cooling water from the supply pipe 50 to the condenser. The stem 54 of valve 52 10 extends upwardly through a packing box 55 in the casing 51 and carries a roller 56. This valve 52 is opened by a cam 57 fixed to the shaft 41 of the gearing driven by the starting-motor 23. Valve casing 51 is formed 15 with a bracket 58 which is secured to the underside of the supporting bracket 34, to support the valve casing in proper relation to the starting mechanism. This cam 57 is formed to open valve 52 when the motor 23 20 is operated to start the motor 17, to hold the valve open during the operation of said motor and to permit spring 53 to close the valve at all other times. The axis of stem 54 extends 25 towards the axis of shaft 41, so that the force of spring 53 will not be applied to rotate cam 57 when the shaft is at rest and the valve is open.

The passage of water from the chamber 59 in casing 51 above valve 52, to the pipe 16, 30 controls a plunger 60 which is slidably mounted in a cylinder 61 in said casing. The upper side of this plunger is exposed to the pressure of water in chamber 59. A spring 62 serves to lift the plunger and to hold it 35 normally raised with force slightly less than the minimum pressure required for the condenser 12. Plunger 60 is provided with openings 63 which are adapted to pass into registry with a duct 64 leading into the outlet of the casing. The force of spring 62 40 may be adjusted by a screw 66 which engages a cap 67 on the lower end of the spring. This adjustment adapts the device for operation by water under different pressures. If 45 the water supply from pipe 50 should fail or should be below the minimum pressure necessary for proper operation of the condenser 12, plunger 60 will keep the outlet closed. When the motor 23 is operated, water from 50 the pipe 50, under sufficient or normal pressure, will pass into the upper end of cylinder 61 and force plunger 60 downwardly against the force of spring 62, to bring ports 63 into 55 registry with the duct 64 and cause the water to flow through the casing to the condenser as long as valve 52 is held open. Upon closing of valve 52, which occurs when the operation of the compressor ceases, 60 spring 62 will restore plunger 60 to the normal position shown in Fig. 1, it being under-

stood that there will be a slight leakage between the plunger 60 and the cylinder 61, so that the water confined in the upper portion of the casing can escape. This exemplifies a controlling device operated by the cooling liquid and is used to control the operation of the motor 17 so that said motor and the compressor will not be operated to compress the refrigerant, except when water of the necessary minimum in volume or pressure is being supplied to the casing 51.

Plunger 60 is provided with a stem 69 extending through a packing-box 71 in the head 70 of the cylinder 61 and the upper end of this stem is guided in a socket 72 on bracket 58. A collar 73 is secured adjacent the upper end of stem 69 and has abutments 76 to shift a lever 74 for operating the switch-lever 22. Lever 74 is pivoted, as at 75, to the bracket 58, and extends between 80 abutments 76 on collar 73. The distal end of lever 74 is pivoted, as at 75', to an arm 77, which is pivoted, as at 78 to a lug 79 on a member 80 of a casing for the switch. A link 81, pivoted as at 82, to the distal end of 85 the switch-lever 22, is slideable longitudinally in the hub of arm 77. A head 83 on the lower end of link 81 acts as a one-way stop between link 81 and arm 77. A spring 84 coiled around link 81, is interposed between 90 the hub of arm 77 and the outer end of the link. When the water forces the plunger 60 downwardly to permit the water to flow to the condenser, the upper abutment 76 will force lever 74 downwardly. Such movement 95 will rock arm 77 and link 81 about the pivot 78. The link 81 and lever 22 which is adapted to cross the dead center to render spring 84 active to quickly snap the lever 22 into the switch-member 21. Likewise, the spring 100 81 serves to move the lever 22 outwardly after the linkage has passed the dead center during the shift of lever 74 to open the switch. The abutments 76 are formed to leave sufficient lost motion between them 105 for the lever 74 so that even though the plunger 60 is moved slowly downwardly, a quick shift of lever 22 will result. The hole in lever 74 for pivot 75' is elongated to permit the lever to move longitudinally slightly, 110 responsive to the arcuate movement of pivot 75'. This mechanism exemplifies motor-controlling mechanism controlled by the water in the valve-casing 51 through which water passes to the condenser, and also mechanism 115 for effecting a quick shift of the switch lever to avoid sparking at the contacts, particularly when the movement of controlling plunger 60 is slow.

The operation of the system will be as 120 follows: Assuming the apparatus to be at rest, valve 52 will be closed and the switch-lever 22 will be in position to interrupt the circuit for the motor 17. The starting-motor will also be at rest, because the circuits 130

- therefor are interrupted. When the temperature rises to the predetermined maximum, thermostat 24 will touch contact 29, whereupon, a circuit for causing motor 23 to operate will be established as follows: line conductor 18, conductor 28, contact 29, thermostat 24, contact 32, controller 30, contact 31, conductor 26, motor 23, conductor 25 and line-conductor 19. The starting 10 motor will then operate to rotate shaft 41 one-half revolution. Controller 30 is provided with an interrupter notch 30^a which is normally in position to break the contact between member 30 and contact 33. When 15 shaft 41 has completed a half revolution, the notch 30^a will be brought into position to be disposed at contact 31, whereupon, said circuit will be interrupted causing the motor 23 to stop. 20 When the shaft 41 has been thus operated cam 57 will be in position shown in Fig. 1 and the valve 52 will be open. If water under sufficient pressure for condensing is being supplied to casing 51 by pipe 50, 25 plunger 60 will be forced downwardly by the water to bring ports 63 and ducts 64 into registry, whereupon, water will flow through pipe 16 to the condenser. Such shift of plunger 60 will also operate lever 74 to shift 30 switch-lever 22 against contacts 21, 20, to close the circuit for operating the motor 17 which drives the compressor 10. Thereupon, the refrigerant will be compressed and circulated through the refrigerating 35 line and cooling water will flow to the condenser. If there is no water in pipe 50, or if it is insufficient to force plunger 60 downwardly against the force of spring 62, the mechanism for controlling motor 17 40 will not be operated and said motor will remain idle, thus preventing damage to the system, resulting from operating the compressor while the condenser is inoperative through lack of or deficient water supply. 45 If the water supply is sufficient and lever 74 has been operated to cause the motor 17 to operate the compressor, the starting motor 23 will remain idle until the temperature in the refrigerating room or space has been 50 lowered to the desired minimum, whereupon, thermostat 24 will move against contact 27, and a circuit for the operation of the starting motor will be established as follows: line conductor 18, conductor 28, contact 33, 55 controller 30, contact 32, thermostat 24, contact 27, conductor 26, motor 23, conductor 25 and line-conductor 19. The operation of motor 23 will continue until notch 30^a passes into normal position indicated in Fig. 60. As the notch 30^a passes contact 32, the circuit for motor 23 will not be interrupted because the current will pass from conductor 28 to contact 31 via contact 33 and controller 30. Before the controller reaches its normal position and motor 23 stops, cam 57 will 65 be in position to permit spring 53 to close valve 52 and cut off the supply of water to the condenser. As a result, spring 62 will lift plunger 60, the water above the plunger 60 escaping between the plunger and cylinder 61 into the outlet. This movement of the plunger will lift lever 74 to open shift-switch lever 22 to its open position. Whereupon, the operation of motor 17 and compressor 10 will be discontinued until it is again necessary or until the thermostat 24 is operated responsively to the raising of the temperature in the refrigerating room or space.
- The invention thus exemplifies a refrigerating system in which provision is made for automatically controlling its operation by the supply of cooling water for the refrigerating system and in which the compressor will not be operated when the water supply fails or is insufficient in pressure to effect condensation or the cooling desired. Also one in which provision is made for a quick shift of the switch-lever for controlling the operation of the motor for driving the compressor, responsive to slow movement of the shifting mechanism. Also one in which the starting motor, by means of gearing, operates a cam for shifting the spring-closed water-valve. Also one in which the controlling mechanism for starting the motor is simple in construction.
- The invention is not to be understood as restricted to the details set forth, since these may be modified within the scope of the appended claims, without departing from the spirit and scope of the invention.
- Having thus described the invention, what I claim as new and desire to secure by Letters Patent, is:
1. In an automatic refrigerating system, the combination of a compressor, a motor for operating the compressor, a condenser, means for supplying cooling liquid to the condenser, slideable spring-closed means controlled by the cooling liquid, for controlling the operation of the motor and whereby it will be caused to remain inoperative if the supply of cooling liquid is insufficient, a spring-closed slide valve for controlling the supply of liquid; and casing containing said valve and said controlling means.
  2. In a refrigerating system, the combination of a compressor, a motor for operating the compressor, a valve for controlling the supply of cooling liquid to the system, a starting motor, a shaft, gearing between said starting motor and said shaft, means operated by said shaft for operating said valve, and pressure-means operated by the pressure of the cooling liquid, for controlling the operation of the compressor-motor.
  3. In a refrigerating system, the combination of a compressor, a motor for operating the compressor, a valve for controlling the

4. In a refrigerating system, the combination of a compressor, a motor for operating the compressor, a valve for controlling the supply of cooling liquid to the system, a starting motor, a shaft, gearing between said starting motor and said shaft, means operated by said shaft for operating said valve, and pressure-means operated by the cooling liquid for controlling the operation of the compressor-motor.
5. In a refrigerating system, the combination of a compressor, a motor for operating the compressor, a valve for controlling the supply of cooling liquid to the system, a starting motor, a shaft, gearing between said starting motor and said shaft, means operated by said shaft for operating said valve, and pressure-means operated by the cooling liquid, for controlling the operation of the compressor-motor, a thermostat, a circuit-controller operated by said shaft and connections between said controller and said thermostat.
6. In a refrigerating system, the combination of a compressor, a motor for operating the compressor, a valve for controlling the supply of cooling liquid to the system, a starting motor, a shaft, gearing between said starting motor and said shaft, a cam on said shaft for operating said valve, and pressure-means operated by the cooling liquid, for controlling the operation of the compressor-motor, a thermostat, a circuit-controller fixed on said shaft and connections between said controller and said thermostat.
7. In a refrigerating system, the combination of a compressor, a motor for operating the compressor, a switch for said motor, a spring-closed valve for controlling the supply of cooling liquid to the system, a starting motor, a shaft, gearing between said starting motor and said shaft, a cam on said shaft for operating said valve, and spring-shifted pressure-means operated by the cooling liquid for shifting said switch, a thermostat, a circuit-controller fixed on said shaft and connections between said controller and said thermostat.
8. In an automatic refrigerating system, the combination of a compressor, a motor, thermostatically controlled means and connections for controlling the operation of said motor, gearing driven by said motor comprising a shaft, said connections controlling the motor to operate the shaft successive partial revolutions, a valve for controlling the supply of liquid to the system, and means operated by said shaft for operating said valve.
9. In an automatic refrigerating system, the combination of a compressor, a motor, thermostatically controlled means, and connections for controlling the operation of said motor, gearing driven by said motor comprising a shaft, said connections controlling the motor to operate the shaft successive partial revolutions, a valve for controlling the supply of cooling liquid to the system, a spring for operating the valve in one direction, and a cam on said shaft for operating said valve in the opposite direction.
10. A refrigerating apparatus comprising a compressor, a condenser and a refrigerating chamber, a valve for controlling the flow of cooling medium through the condenser, an electric motor for actuating the valve, circuit-changing devices controlled by the motor in actuating the valve and thermostatic means including circuit connections, said thermostatic means being electrically connected to the circuit changing means controlled by the motor and being located in operative relation to the refrigerating chamber.
11. A refrigerating apparatus comprising a compressor, a condenser, a refrigerating chamber, and an electric-mechanical unit responsive to temperature changes in the refrigerating chamber, comprising an electric motor, valve means for controlling the flow of cooling medium through the condenser, electric switch means for the motor, and mechanical connections between the motor and the switch means and valve means, whereby cooling medium may be supplied and cut off from the condenser.
12. A refrigerating apparatus, comprising a compressor, a condenser and a refrigerating chamber, a valve for controlling the flow of cooling medium through the condenser, an electric motor for actuating the valve, circuit-changing devices for controlling said motor, thermostatic means electrically connected to said circuit-changing devices located in operative relation to the refrigerating chamber, and mechanism comprising speed-reducing gearing operated by said motor for operating said circuit-changing devices and said valve.
13. In an automatic refrigerating system, the combination of a compressor, a motor for driving the compressor, a starting motor, thermostatically controlled means and connections for controlling the operation of the starting motor, reducing gearing driven by the starting motor and comprising a shaft for operating said controlling means and connections, a valve for controlling the supply of liquid to the system, and means operated by said shaft for operating said valve.
14. A refrigerating apparatus, comprising

a compressor, a condenser, a refrigerating chamber and an electro-mechanical unit responsive to temperature changes in the refrigerating chamber comprising an electric 5 motor, valve means for controlling the flow of cooling medium through the condenser, electro-circuit-changing means for said

motor, and mechanical connections between the motor and the circuit-changing means and valve means comprising reducing gearing operated by said motor, whereby cooling medium may be supplied and cut off from the condenser.

CHARLES C. HANSEN.
